UNITED STATES PATENT OFFICE.

PETER ALEXANDER VOGET, OF HANOVER, GERMANY.

SHORTHAND TYPE-WRITING MACHINE.

SPECIFICATION forming part of Letters Patent No. 767,508, dated August 16, 1904.

Application filed December 11, 1902. Serial No. 134,795. (No model.)

To all whom it may concern:

Be it known that I, PETER ALEXANDER VOGET, a subject of the German Emperor, and a resident of Hanover, in the Kingdom of 5 Prussia and Empire of Germany, have invented certain new and useful Improvements in Shorthand Type-Writing Machines, of which the following is a specification.

The invention relates to improvements in 10 shorthand type-writing machines, and has for its object to render it possible to take down notes, words, phrases, speeches, and the like.

In the drawings, Figure 1 is a view showing 15 the method of printing the characters at different relative positions with relation to a fixed line. Fig. 2 is a sectional end view of the type of printing mechanism used in the Hammond type-writer provided with my improved mechanism.

20 The mechanical construction of this shorthand type-writer is seconded by a peculiar writing system founded upon principles similar to the rules of stenography.

For the purpose of explaining the feature 25 of the new machine I shall proceed to instance a few examples, by means of which it will be obvious which shorthand rules are employed in my improved shorthand type-writer.

The vowels are not always written, but frequently indicated by means of a symbol in 30 such a manner that by the elevation (higher position) of a consonant the character "e" is indicated, by the low position (lower position) an "oo," by a heavy-faced type the letter 35 "a," and so on.

In Fig. 1 of the annexed drawings several examples of such a vocalization are given, which are so to be read: 1, "beer;" 2, "book;" 3, "bar." Each one of these three characters 40 is expressed by two letters only, thus rendering possible a great saving of time. Combinations of consonants frequently used—for instance, "st, sh, cr, ch"—are combined upon one key. Consequently in Fig. 1, read on: 45 4, "steam;" 5, "shoe;" 6, "chalk." The words "steam" and "chalk" also need only two strokes, the word "shoe" even one only. Prefixes and affixes frequently recurring—for instance, "con," "tion"—also independent parts of speech—for example, "and,"

"from," and so on—are combined on one key alone. In this way it is possible to produce the word "constriction," which has twelve letters, on my shorthand type-writer by means of but four strokes of the keys—to wit., 55 first, "con," second, "str," in elevation, thereby expressing the character "i;" third, "c;" fourth, "tion."

In Figs. 2, 3, and 4 three examples of mechanical constructions of the new machine 60 are shown.

Nearly every type-writer can be arranged for the present object by a corresponding modification or completion of its parts.

In Fig. 2 a Hammond machine is chosen 65 for example, wherein 1 indicates the well-known type-shuttle; 2, the type-hammer behind the paper 3 to be written on. 4 are the paper-conducting rolls. 5 is one of a series of printing-keys, which when pressed 70 down causes a small letter to appear. Around the fixed pivot 6 swings a lever carrying the key 7. When key 7 is struck, the free end 8 of this key-lever lifts the shaft 9 of the type-shuttle 1 so far that instead of the small 75 type 10 the large type 11 comes in contact with the paper 3. So far the former arrangement of the Hammond machine has been left unchanged. For the purpose of the shorthand-writing machine, however, the capital 80 letters 11 (initials) may be replaced by small heavy-faced letters.

The following arrangement serves for the purpose of adjusting the type-shuttle 1 a little higher or lower, so that one can cause both 85 the small type 10 and the large type 11 to be printed a little above or below the line, as will be seen from Fig. 1. Consequently the type-shuttle of the Hammond machine formerly having only an elevation and a low position now has all in all six positions.

Around the pivot 6 referred to swings a three-armed lever 12 13 14. The lever-arm 13 is pushed upward when the key 15 is struck. When, however, the key 16 is pressed down, 95 the lever-arm 12 is lifted. These movements are accomplished by means of the levers swinging around the pivots 17 and 18, as will be at once visible from the drawings. The three levers 12 13 14, oscillating around pivot 6, 100

form a rigid device and by means of the connecting-rod engaging at arm 14 transmit their rotations to the lever 19, swinging around the pivot 8 and forming a solid whole with the 5 cam 20. The position of the parts 14 19 20 (shown in the drawings) is their central one. According as the cam 20 is raised more or lowered more the shaft 9, together with the shuttle-type 1, will be raised or lowered a little also. An exact delimitation of this movement or stroke is attained by the elongation 10 of the lever 6 8, which oscillates between the fixed points 22 and 23.

The keys are tapped in the following manner: As stated above, by striking the key 5 and pressing against the type 10 a small letter of normal height of handwriting is produced—for example, the "r" in "beer," Fig. 1, No. 1. When, however, the keys 5 and 7 are 15 tapped at the same time, the heavy-faced type 11 appears—for instance, the "b" in the word "bar," Fig. 1, No. 3. If 5 and 15 are struck at the same time, the type-shuttle 1 sinks down a little, because the key 15 through the medium of the intermediate links 17 18 14 19 20 transmits its movements to the cam 20, lowering the latter, so that the shaft of the type-

shuttle also goes down. This produces, for instance, the letter "b" of the word "book," Fig. 1, No. 2. The same will be the case on 30 a simultaneous tapping of the three keys 5, 7, and 15 as to the heavy-faced type 11. A corresponding result will be attained when 5 and 16 or 7 and 16 are pressed down at the same time, as the corresponding letter will then appear above the line of writing.

Having now fully described my invention, I declare that what I claim is—

In a shorthand type-writing machine, the combination of an adjustable type-shuttle, 40 means for printing with said shuttle, a shaft on which said shuttle is mounted, a lever for raising and lowering said shaft, a cam on said lever, a shaft on which said lever is pivoted, a three-armed lever pivoted on said shaft, a 45 rod connecting one of said arms with said cam, levers connecting with said other arms and keys for operating said last-named levers.

In testimony whereof I affix my signature in presence of two witnesses.

PETER ALEXANDER VOGET.
